afftest,

Henry Bullard
Atto. Wood

Inventor,

Charles B. Beall
By Frank Millward
Attorney

United States Patent Office.

CHARLES B. BEALL, OF HAMILTON, OHIO.

Letters Patent No. 97,858, dated December 14, 1869.

IMPROVEMENT IN HEAD-BLOCKS FOR SAW-MILLS.

The Schedule referred to in these Letters Patent and making part of the same.

To all whom it may concern:

Be it known that I, CHARLES B. BEALL, of Hamilton, Butler county, State of Ohio, have invented certain new and useful Improvements in Head-Blocks for Saw-Mills; and I do hereby declare the following to be a sufficiently full, clear, and exact description thereof, to enable one skilled in the art to which my invention appertains, to make and use it, reference being had to the accompanying drawings, making part of this specification.

My invention consists of certain devices for feeding the "knee" of the head-block forward, and, also, peculiar devices for permitting the same to be readily disconnected from the feed, and drawn back.

In the accompanying drawings—

Figure 1 is a perspective view of a head-block and connections, embodying my invention.

Figure 2 is a perspective view of the feeding-racks.

Figure 3 is a view of the under side of the "knee," showing the devices for disconnection.

Figure 4 is a side elevation of the knee.

Figure 5 is a plan, exhibiting the shape of the sliding block, which operates the feeding-racks.

A A' are the ways or rails of an ordinary saw-mill, and B C, a "head-block" and "knee," respectively, embodying my invention or improvements.

In the interior of the head-block B, two racks, E E', are located, which, by alternate forward motion, serve to feed the "knee" C forward, by connection with pawls D D' of the knee.

The backward motion of the racks is obtained by means of the lever F, the forward motion of each rack serving, by connection with lever F, in the manner shown, to push the other back.

A spring, G, between the ends of the racks and the lever, serves to take up lost motion in the moving parts.

To the racks E E', I secure anti-friction rollers H H, suitably journaled in jaws e e', of the racks.

These rollers are acted upon by the device which I have designed to give motion to the racks, which consists of a block, L, which slides in bearings I I', and is operated by the lever J and bar K.

This bar K is continued to the other end of the mill, and is connected to similar devices to the oppo-

site head-block, so that both may be fed simultaneously.

If necessary for the head-blocks to act independently, one of the blocks L may slide upon the bar K loosely, and be acted upon by an independent handle-
lever.

The block L is constructed as clearly shown in fig. 5, viz, with one or more curved prominences l, and one or more depressions l'.

The racks are adjusted so that the roller of one may rest at the deepest point of the depression, while that of the other is at the highest point of the prominence, so that the movement of the block L backward and forward, by means of lever J, will give a reciprocating motion to the racks E E'. The block L may be adjusted on the bar K, by set-screw M.

The knee C is fitted with a key, N, which has a flattened projection or cam, n, on the end, and also with a double-ended spring, O, and spring pawls P P', which are thin enough to spring of themselves, to allow the racks E E' to move back, and are pivoted or hinged to the knee at p p'.

The position of the cam n and pawls P P', when in operation, is seen in fig. 3, the ends of the pawls being then fully extended, (the spring O serving to keep them so,) in order to engage with the racks E E'.

It will be seen, by reference to fig. 3, that by turning the key N a quarter of a revolution, the outer ends of the pawls P P' are thereby contracted sufficiently to permit of the knee C being drawn back, and, if necessary, entirely removed from the head-block.

I claim herein as new, and of my invention—

A head-block for saw-mills, combining in its construction a bed-plate for the log to rest upon, two racks E E', with friction-rollers H H in the outer ends, a spring and oscillating lever at their inner ends, a cam-shaped slide, L, for operating the racks, and a knee, C, constructed as described, all arranged and operating as and for the purpose set forth.

In testimony of which invention, I hereunto set my hand.

Witnesses:

CHAS. B. BEALL.

I. S. WARTMANN,
FRANK MILLWARD.
